UNITED STATES PATENT OFFICE.

ALBERT HALSTEAD, JR., OF MILWAUKEE, WISCONSIN.

APPARATUS FOR CURVING PRINTING PLATES.

Application filed January 4, 1926. Serial No. 79,101.

It is the object of my invention to provide a simple means for curving printing plates in such manner as to maintain the relations of their printing lines; further, to provide novel means whereby a printing plate is curved about an integral forming portion of a forming mold; further, to provide novel means for curving a printing plate between a forming mold and a flexible band under tension arranged to wrap the printing plate about the forming mold rolling thereover; further, to provide novel means whereby forming molds of different diameters may be substituted one for the other; and, further, to provide supporting means, a tension band above said supporting means, and novel means whereby said band is positioned with relation to the supporting means to accommodate forming molds of different diameters.

The invention will be further readily understood from the following description and claims, and from the drawings, in which latter:

Fig. 1 represents a front elevation of my improved device.

Fig. 2 is a rear elevation of the same.

Fig. 3 is a sectional detail taken on the irregular line 3—3 of Fig. 2.

Fig. 4 is an end elevation of my improved device.

Fig. 5 is a plan view of the same, partly in section on the line 5—5 of Fig. 4.

Fig. 6 is a vertical cross-section of the same, taken in the plane of the line 6—6 of Fig. 5, but showing the gaging means and the pressure means for the printing plate in depressed position.

Fig. 7 is a sectional detail taken on the line 7—7 of Fig. 5.

Fig. 8 is a vertical longitudinal section of my improved device, taken on the line 8—8 of Fig. 5, showing a mold of larger diameter and the parts adjusted for accommodating the same.

Fig. 9 is a similar view, partly broken away, showing a mold of smaller diameter and the parts adjusted for accommodating the same.

Fig. 10 is a plan view of a printing plate adapted to be curved in my improved device.

Fig. 11 is a vertical longitudinal section of the same, taken on the line 11—11 of Fig. 10.

Fig. 12 is a vertical cross-section of the same, taken on the line 12—12 of Fig. 10; and,

Fig. 13 is a vertical cross-section, taken in the plane of the line 12—12 of Fig. 10, showing the printing plate in curved form.

My invention is especially applicable for curving printing plates for mounting the same on so-called plate cylinders in rotary printing presses. Such plate cylinders are of different diameters on different presses, and I therefore further provide means whereby the printing plates may be curved to curvatures of different diameters for coaction with plate cylinders of different diameters.

In accomplishing the curving of the printing plate I employ a rollable mold and a flexible band between which and the rollable mold the printing plate is received. I further employ means for maintaining the flexible band under tension while it and the printing plate are being wrapped about the rollable mold, thereby bending the printing plate to a curvature corresponding to the curvature of the periphery of the rollable mold, determined by the diameter of said mold. In order to render the printing plate more readily bendable, I prefer to subject the same to heat prior to the bending thereof. The curved printing plate produced by employment of my invention has the printing lines of its printing surface maintained in the spaced relations which they occupied prior to the curving of the printing plate.

In the present exemplification there is a forming mold 21 having an outer periphery 22 in the form of a substantial part of a cylinder. The forming portion of the mold which coacts with the printing plate is preferably integral.

A frame 23 is provided with racks 24 at the front and rear thereof, and with bearers 25 proximate to the racks. The forming mold is provided with gears 26 at the respective ends thereof, adjacent to which there are annular bearers 27. The gears mesh with the racks, and the annular bearers coact with the bearers on the frame, so as to

2
5 maintain relative distance between the cylindrical surface of the forming mold and a printing plate support 28, above which the printing plate, represented at 31, is arranged to be supported during the curving operation.

10 The printing plate is exemplified as a printing plate in unfinished state, and as having the usual bearers 32, 33, separated from the printing surface 34 by the usual grooves 35, 36, and if desired, the rear face of the backing of the printing plate may be provided with recurrent depressions 37, forming ribs 38, which may extend in any 15 desired direction across the back of the printing plate.

20 The printing plate may be formed in any ordinary or usual manner and be for instance an electroplate comprising a printing shell 39 of electro-deposited metal, having a higher fusing point, and a backing 40 of metal or material having a lower fusing point, although printing plates otherwise formed may be curved by my improved apparatus.

25 The support may be in the form of a heater, comprising a slab of desirable metal for readily transferring heat, and heated in suitable manner, as by means of electric heating elements 41, which may be in the form of usual electric resistance strips, suitably insulated, and held to the supporting slab by cross cleats 42, these heating elements being provided with electric terminals 43, 44, connecting with bus-bars 45, 46, with which the electric connections from a suitable source of electric supply may connect, suitable heat controlling and regulating and switching devices being located in the electric circuit for proper regulation and control of the heat for the heating slab.

30 The heating slab may be supported on suitable flanges 48 extending from the frame, and separated from said flanges by suitable insulating blocks 49, to avoid transference of said heat from the slab to the frame.

35 The printing plate is arranged to be placed on a bending element shown as a flexible band 51, hereinafter more particularly described, supported by the support, with the printing surface 34 of the printing plate presented toward said support. If desired, a suitable cushioning sheet 52, as of oil-saturated book-paper of ordinary thickness, is interposed between the flexible band and the printing plate.

40 Means may also be provided for pressing the printing plate toward the slab during the heating of the plate, instanced as accomplished by means of presser feet 54 located in socket-pieces 55 depending from guides 56, slidable along pressure bars 57, and held in adjusted positions by set-screws 58. Pressure shoes 59 of greater area may also be

50 provided, suitably secured to the lower ends of presser-stems 60, extending from guides 61, also adjustable lengthwise of said pressure bars, and clamped in adjusted positions by set-screws 62.

55 The pressure bars are provided with bearings 65 adjustable lengthwise of a rock-shaft 66 and with bearings 67 adjustable lengthwise of a rod 68, fixed to arms 69 fixed to the rock-shaft. The pressure bars are adjustable laterally for placing the presser feet and presser shoes in desired positions with relation to the printing plate, the bearings 65 being fixed to the rock-shaft 66 in adjusted positions by means of set-bolts 70.

60 The rock-shaft 66 is journaled in bearings 71 on brackets 72 extending from the frame. Counterweights 73 are fixed to the rear overhanging ends of the pressure bars for normally moving the pressure bars into out-of-the-way position.

65 The pressure bars are held in down position for maintaining pressure of the pressure feet and pressure shoes upon the printing plate during heating of the latter, as by means of latches 75 arranged to engage a latching bar 76 on the frame. These latches are pivoted on pins 77 in forks 78 at the forward ends of the pressure bars, being normally urged into engaging relation with the latching bar by means of springs 79. Stops 80 limit the swinging movements of the latches toward the latching bar, for ready passage of the latching end of the latches along the side of the frame into latching engagement with the latching bar. The latches are readily released by the operator pulling on handles 81 thereon.

70 The printing plate is positioned parallel with the axis of the mold, so that the curvature of the latter shall be parallel with the printing plate. This positioning is aided by means of gages 85, adjustable on arms 86, and held in adjusted positions by set-screws 87, the arms 86 being adjustable laterally by having their bearings 88 adjustable lengthwise on a rod 89, and fixed in adjusted positions by set-screws 90. The rod 89 is fixed to arms 91 having bearings 92 about the rock-shaft 66. One of the pressure bars is provided with a latch 93, pivoted thereto on a pivot 94, in such relation to the rod 89, that when the pressure bars are depressed, the latch 93 will automatically be received about the rod 89, so as to cause the gages 85 to rise with the pressure bars 57. If it is desired to place the gages 85 in gaging position, the pressure bars are depressed, and release of the latch 93 is effected, for instance, by means of a pull-rod 95, having articulation with the latch at 96, and supported in eyes 97 on one of the pressure bars. A collar 98 and a spring 99 position the pull-rod. When now the pressure bars are allowed to rise, the gages remain in position 130

for gaging the placing of the printing plates.

The retraction of the pressure bars may be cushioned by a spring 101 extending between an arm 102 secured to the rock-shaft 66 and the frame, the spring being located about a rod 103 articulated with said arm and between a collar 104 on said rod and a bearing 105 on the frame through which said rod slides.

10 The rock shaft 66 is provided with an arm 106. A link 107 is articulated with the arm at 108 and with a bell-crank lever 109 at 110. The bell-crank lever is pivoted on a stud-shaft 111 extending from the frame.

15 A treadle lever 112 in the form of a bell-crank is pivoted to the frame on a stud-shaft 113. A link 114 is articulated at 115 with the bell-crank lever 109 and at 116 with the treadle lever.

20 When the treadle lever is depressed, the arm 106 is caused to descend, thereby causing the pressure bars to descend for pressing relation of the pressers thereon with the printing plate, the latches 75 engaging the latching bar 76. When the printing plate has been properly heated, the latches are released, whereby the counterweights cause 25 the pressure bars to rise, carrying with them the gages 85 and the parts, on which the same are mounted.

The printing plate is preferably placed in a position above the heating slab with its side edges 117 substantially equi-distant from the side edges 118 of the heating slab, 35 in order that the most uniformly heating part of the heating slab may act upon the printing plate for heating the latter uniformly throughout its area.

If desired, the heating may be of such 40 temperature and duration as to cause a heat condition of the backing material which is near its point of fusion at the time of curving, and may further, if desired, be according to the teachings of the Claybourn Patent No. 1,318,967, dated October 14, 1919, 45 for method of curving printing plates and printing plates curved thereby.

The presser feet and presser shoes and the pressure bars and latching means therefor, 50 and the gaging means, may be substantially as shown and described in Letters Patent No. 1,372,064, to L. W. Claybourn, dated March 22, 1921, for apparatus for curving printing plates.

55 The rollable mold 21 is provided with trunnions 121, journaled in bearings 122, received in guideways 123 of end-frames 124. The bearings are shown provided with slots 125, in which the side walls of the guideways 123 are received for positioning said 60 bearings endwise.

The end frames are provided with inwardly extending studs 127, on which rollers 128 are held endwise, the rollers being rotatable about said studs and rolling length-

wise of guideways 129 in the front and rear walls of the main frame. The lower and upper walls of the guideways support the end frames and prevent rise of the same.

70 A cross-shaft 131 connects the end frames, being journaled in bearings 132, 133, therein, and having pinions 134 fixed thereon, which pinions mesh with the racks 24. A collar 135 is fixed to one end of the cross-shaft, and a hand-wheel 136 is fixed to the other end thereof. The end frames are positioned lengthwise of the cross-shaft between the pinions 134, fixed to said shaft, at the inner faces of said end frames, and the collar 135 and hand-wheel 136 at the outer faces of said end frames, forming a carriage 80 for controlling the movement of the rollable mold.

85 When the cross-shaft is rotated, the pinions rotate with relation to the racks, causing the end frames to move parallel with each other lengthwise of the racks, this movement of the end frames and carriage causing the rollable mold to roll in parallel lines by reason of the meshing of its gears 90 at its respective ends with said racks, in order that parallel bending of the printing plate is effected.

95 One end of the flexible band has connection with the rollable mold, and the other end of the same is held by a relatively stationary part, for causing a wrapping of said flexible band and the printing plate thereon about the rollable mold, when the latter is 100 rolled over the printing plate.

The connection between the end of the flexible band and the rollable mold is preferably releasable. This may be accomplished by a hook-bar 141, extending lengthwise of the mold, and provided with a longitudinal 105 groove 142, releasably received over a lip 143 of said mold. The flexible band may be secured to said hook-bar by rivets.

The outer wall 144 of the hook of said bar is preferably of a thickness to correspond to the thickness of the printing plate, 110 in order to provide a printing plate space 145 between the flexible band and the periphery of the mold.

115 The other end of the flexible band is provided with anchoring means. Thus the flexible band may be provided with a cross-strip 146, to which the flexible band is secured, as by riveting the same thereto.

120 A positioning bar 150 extends crosswise of the frame, its ends being formed as tongues 151 received in and guided by the walls of guideways 152, in guide-bars 153, on brackets 154 of the frame. Adjusting screws 155 are journaled in the ends of said 125 guide-bars, and threaded into threaded holes in said positioning bar, the threaded rods being provided with turning means, as handles 156, for turning the same, and thereby 130 adjusting the position of said positioning

bar, and consequently the position of the flexible band, with relation to the rollable mold and the heating slab.

- 5 Springs 157 are preferably interposed between the flexible band and the positioning bar for providing continuous tension upon the flexible band. The respective ends of these springs are fixed respectively to the cross-strip 146 and the positioning bar 150.
- 10 The latter connection is shown formed by the threaded ends 158 of the springs projecting through holes in said positioning bar, nuts 159 being threaded to said threaded ends for regulating the tensions of said respective springs.

Rollable molds of different diameters may be selectively placed in the curving machine, the diameters of these molds being determined by the diameters of the curvatures to which the printing plates shall be curved to fit plate cylinders of different diameters.

Thus I have shown a rollable mold of larger diameter in Fig. 8, and a rollable mold of smaller diameter in Fig. 9. Rollable molds of intermediate diameters may also be provided. Each of the molds is provided with a coacting lip 143, with which the hook-bar of the flexible band is arranged to releasably connect.

30 Each of the rollable molds is so placed in the machine that the middle portion of its forming periphery, instanced at 161, shall coact with the middle portion 162 of the printing plate which is centrally placed upon the heating slab. I have found that best results are obtained by this relation, for the reason that the printing plate is thus subjected to most uniform heat throughout its area, and the most desirable portion of

40 the periphery of the rollable mold coacts with the printing plate.

This most desirable portion is backed by a cooling agency, which may be a body of water in a cooling chamber 165 in the mold.

45 The water may be introduced into said chamber by means of hoses 166, 167, connecting with said chamber by means of nipples 168, 169, and leading respectively from a suitable source of supply and to a waste pipe, the hoses being connected with suitable valves, not shown, for regulating the supply of cooling fluid and the heat of the cooling agency in the chamber.

55 The adjusting means for the anchored end of the flexible band are provided for shifting the flexible band laterally, in order to compensate for different diameters of rollable molds, and the different positions of the connection of the flexible band therewith, for effecting proper corelation between said rollable mold and the printing plate placed as stated on the heating slab. It will be noted by a comparison of Figs. 8 and 9, that the greater the diameter of the rollable mold, the greater is the distance of the connection

of the flexible band therewith from the median portion of the heating slab when said rollable mold is in retracted position.

Means are provided for limiting retraction of the carriage controlling the molds of different diameters. In order to correctly position the carriage in the retracted position, I provide an adjustable stop, shown as a lug 171 on the slide frame, and a coacting stop 172 in the form of a pin insertable in holes 173 in the frame, the various holes corresponding to the various molds of different diameters it is desired to employ in the machine.

Means are provided for readily inserting and removing molds of different diameters, as by providing the bearings 122 thereof with rings 175, into which suitable lifting hooks of suitable power or hand lifting devices may be connected, for readily raising and lowering said molds, and for causing proper meshing relation between the gears of said molds and the racks on the machine, in order to produce proper desired correlated movement between said molds and the heating slab.

After the printing plate has been curved, (see Fig. 13), it may be submitted to subsequent operations of shaving the inner face of the printing plate, solidifying, and correcting the same, and trimming the edges thereof, in any desired manner.

In operation, the mold carriage is adjusted to its proper retracted position, according to the diameter of mold which it is desired to employ, as by placing the adjustable stop pin 172 in its proper hole 173, and retracting the carriage so that its stop 171 coacts with the stop 172.

The desired rollable mold is then inserted in the carriage, and the teeth of its gears brought into mesh with the teeth of the rack. The hook-bar 141 is then placed over the lip 143 of the mold, and the flexible band 51 brought under proper tension by adjustments of the adjusting screws 155.

The gages 85 having been adjusted and lowered, the printing plate is placed above the flexible band, with its side edges equidistant from the side edges of the heating slab, the positions of which latter side edges may be indicated on the frame by marks 176.

120 The presser feet and presser shoes having been suitably adjusted, the pressure bars are lowered for effecting pressure upon the printing plate, for pressing the printing plate toward the heating slab for uniform heating of the printing plate. When the printing plate has been subjected to sufficient heat for the desired length of time, the pressure bars are released for raising the same.

125 Turning of the hand wheel 136 causes parallel movement of the carriage and parallel rolling of the rollable mold toward 130

and over the printing plate for rolling the flexible band and the printing plate about the rollable mold. This rollable mold is exemplified as a solid cylindrical mold, an integral portion of the cylindrical surface coacting with the entire printing plate.

When the printing plate has been formed about the rollable mold, it is subjected to the cooling agency in the mold for cooling the printing plate.

The flexible band under tension and the printing plate are wrapped about the rollable mold, for instance, as shown in dotted lines in Fig. 8. As the rotation of the rollable mold progresses along the rack, the teeth of its gears coat with the teeth of the rack for maintaining the flexible band in stretched relation, and maintaining the rollable mold parallel with relation to the printing plate, which has been placed parallel with relation to it, for insuring proper curvature of the printing plate.

When the printing plate has been thus formed, the carriage is retracted by operation of the hand wheel 136, whereupon the curved printing plate is removed from the machine.

Having thus fully described my invention, what I claim as new, and desire to secure by Letters Patent, is:

1. In a machine for curving printing plates, the combination of a rollable mold, a flexible band, means attaching one end of said band to said mold, means anchoring the other end of said band substantially stationary with relation to said rollable mold, the circumference of said rollable mold having an integral printing plate resisting surface, and means whereby to roll said mold and thereby wrap said flexible band about said mold with the printing plate between said flexible band and said integral surface throughout the area of the printing plate.

2. In a machine for curving printing plates, the combination of a rollable mold having a plate curving circumference representing the greater portion of a cylinder, a flexible band, means attaching one end of said band to said mold, means anchoring the other end of said band, and means whereby to roll said mold and thereby wrap said flexible band about said mold in one direction throughout the greater part of the circumference of said mold, with the printing plate located between said flexible band and said mold.

3. In a machine for curving printing plates, the combination of a support, a flexible band thereover, a rollable mold with which one end of said flexible band has connection, and adjustable anchoring means for the other end of said flexible band.

4. In a machine for curving printing plates, the combination of a support, a flex-

ible band thereover, a carriage normally at one side of said support, a rollable mold controlled by said carriage, connecting means between one end of said flexible band and said rollable mold, and anchoring means at the other side of said support for the other end of said flexible band, said anchoring means being substantially stationary with relation to said rollable mold.

5. In a machine for curving printing plates, the combination of a support, a flexible band thereover, a carriage normally at one side of said support, a rollable mold controlled by said carriage, connecting means between one end of said flexible band and said rollable mold, anchoring means at the other side of said support for the other end of said flexible band, said anchoring means being substantially stationary with relation to said rollable mold, and means for adjusting said anchoring means.

6. In a machine for curving printing plates, the combination of a support, a flexible band thereover, a carriage normally at one side of said support, a rollable mold controlled by said carriage, connecting means between one end of said flexible band and said rollable mold, anchoring means at the other side of said support for the other end of said flexible band, said anchoring means being substantially stationary with relation to said rollable mold, and resilient means causing continuous tension upon said flexible band.

7. In a machine for curving printing plates, the combination of a support, a flexible band thereover having a printing plate supporting area, a carriage normally at one side of said support, anchoring means for said band at the other side of said support, a rollable mold whose position is controlled by said carriage, and means connecting said rollable mold with said flexible band, said rollable mold having a printing plate coacting area extending integrally to both sides of the median portion of said first-named area, and arranged whereby said carriage rolls said rollable mold over said support and a printing plate on said flexible band for wrapping said flexible band and said printing plate about said integral coacting area of said rollable mold.

8. In a machine for curving printing plates, the combination of a frame, spaced-apart racks thereon, a rollable mold, gears at its respective ends meshing with said racks, a flexible band, one end of said flexible band having connection with said rollable mold, anchoring means on said frame having connection with the other end of said flexible band, and means maintaining tension on said flexible band, and arranged for rolling said rollable mold toward said anchoring means for wrapping said flexible band and a printing plate between it and

said rollable mold about said rollable mold.

9. In a machine for curving printing plates, the combination of a frame, spaced-apart racks thereon, a carriage, an operating shaft therein, spaced-apart pinions thereon meshing with said racks, a rollable mold for said carriage, gears at the respective ends of said rollable mold coacting with said racks, whereby to move said rollable mold 5 and roll the same lengthwise of said racks, a flexible band, means for attaching said flexible band to said rollable mold, and anchoring means for said flexible band.

10. In a machine for curving printing plates, the combination of a heating slab, a flexible band thereover, pressure means above said flexible band for pressing a printing plate on said flexible band toward said heating slab, a rollable mold normally at one 10 side of said heating slab, anchoring means at the other side of said heating slab, means for attaching said flexible band respectively to said rollable mold and said anchoring means, and means for adjusting said flexible 15 band laterally between said heating slab and said pressure means.

11. In a machine for curving printing plates, the combination of a heating support, a rollable mold normally at one side of said 20 heating support, a flexible band above said heating support, means connecting one end of said flexible band with said rollable mold, anchoring means on said frame for the other end of said flexible band, pressure means 25 for a printing plate above said heating support, and means whereby to retract said pressure means.

12. In a machine for curving printing plates, the combination of a heating slab, a flexible band thereover, pressure means above a d flexible band for pressing a printing plate on said flexible band toward said heating slab, a rollable mold at one end of said flexible band, anchoring means at the other end of said flexible band, means attaching said flexible band to said rollable mold and said anchoring means, means for moving said rollable mold for wrapping said flexible band, about said rollable mold with the printing plate between said flexible band and said rollable mold, and means for adjusting said anchoring means and said moving means laterally with relation to said heating slab.

13. In a machine for curving printing plates, the combination of a frame, a support therein, a flexible band above said support, a rollable mold rollable on said frame over said support, anchoring means, means for laterally positioning said flexible band above said support, and means for connection of the respective ends of said flexible band with said rollable mold and said anchoring means.

14. In a machine for curving printing plates, the combination of a frame, a car-

riage therefor, said carriage arranged for receiving rollable molds of different diameters, means whereby to position said carriage with relation to said frame according to the diameter of mold which it is to receive, a flexible band, means for connecting said flexible band with a mold in said carriage, and anchoring means for said flexible band.

15. In a machine for curving printing plates, the combination of a support, a carriage normally at one side of said support, anchoring means at the other side of said support, rollable molds of different diameters arranged for selective location in said carriage, a flexible band over said support, means connecting said flexible band with the rollable mold in said carriage and with said anchoring means, said flexible band arranged for receiving a printing plate thereover, and means whereby to roll said rollable mold over said support for wrapping said flexible band and a printing plate thereabove about said rollable mold, said respective rollable molds provided with integral peripheries throughout the area of their co-action with the printing plate.

16. In a machine for curving printing plates, the combination of a frame, a support, a carriage normally at one side of said support, said carriage arranged for receiving rollable molds of different diameters, adjustable means limiting retraction of said carriage according to the diameter of mold therein, a flexible band above said support, means connecting one end of said flexible band with the rollable mold in said carriage, and anchoring means for the other end of said flexible band.

17. In a machine for curving printing plates, the combination of a frame, a support, a carriage normally at one side of said support, said carriage arranged for receiving rollable molds of different diameters, adjustable means limiting retraction of said carriage according to the mold therein, a flexible band above said support, means connecting one end of said flexible band with the rollable mold in said carriage, anchoring means for the other end of said flexible band, and means for adjusting said anchoring means according to the adjustment of said first-named adjusting means.

18. In a machine for curving printing plates, the combination of a frame, a support, a carriage normally at one side of said support, said carriage arranged for receiving rollable molds of different diameters, adjustable means limiting retraction of said carriage according to the mold therein, a flexible band above said support, means connecting one end of said flexible band with the rollable mold in said carriage, anchoring means for the other end of said flexible band, means for adjusting said anchoring means

according to the adjustment of said first-named adjusting means, and tensioning means coacting with said anchoring means for maintaining continuous tension on said flexible band.

19. In a machine for curving printing plates, the combination of bending molds having bending surfaces of different curvatures, means for receiving said bending molds selectively in operative position in the machine, flexible band means for said bending molds, and means whereby to roll said respective bending molds with a printing plate and a flexible band means thereabout, whereby to curve said printing plate.

20. In a machine for curving printing plates, the combination of bending molds having bending surfaces of different curvatures, means for receiving said bending molds selectively in operative position in the machine, a support, flexible band means for said bending molds, said flexible band means located on said support, and means

whereby to roll said respective bending molds with a printing plate and a flexible band means thereabout, whereby to curve said printing plate.

21. In a machine for curving printing plates, the combination of bending molds having bending surfaces of different curvatures, means for receiving said bending molds selectively in operative position in the machine, a heating support, flexible band means for said bending molds, said flexible band means located on said heating support, pressure means above said flexible band means for pressing a printing plate on said flexible band means and said flexible band means toward said heating support, and means whereby to roll said respective bending molds with the heated printing plate and said flexible band means thereabout, whereby to curve said printing plate.

In testimony whereof, I have hereunto signed my name.

ALBERT HALSTEAD, JR.
